UNITED STATES PATENT OFFICE.

GEORGE A. PAGONIS, OF NEW YORK, N. Y.

NONREFILLABLE BOTTLE.

Application filed March 31, 1925. Serial No. 19,650.

This invention relates to a non-refillable bottle, and has for an object the provision of simple, efficient and durable parts whereby a bottle can be made non-refillable.

Another object concerns the provision of means whereby the parts are few in number and can be economically manufactured and when assembled on the bottle cannot be removed or tampered with materially without 10 destroying them.

A further object concerns the provision of means which, although simple and durable in construction, will yet at all times permit the proper emission of the contents from the 15 bottle when desired.

The invention is illustrated in the drawings, of which—

Figure 1 is a sectional view of the upper 20 end of the bottle with the parts attached; and

Figure 2 is a plan view of the valve which forms one of the parts of the invention.

The form of the invention shown in the drawings is a preferred form, although it 25 is understood that modifications in the construction and arrangement of the parts and in the character of the materials used may be adopted without departing from the spirit of the invention as set forth in the appended 30 claim.

The invention in its general aspects comprises a metallic cap which is attached over the top end of the bottle and, preferably, crimped over its neck so as to be practically 35 non-removable without being destroyed or broken. This cap is provided with a discharge orifice in which an adjustable member is mounted for adjustment to hold the valve within the cap in a tight position 40 when the bottle is not in use, especially when it is being shipped or stored. Within the cap, and preferably seated on a suitable flexible flange, is a valve which when it is released will move off its seat only when the 45 liquid is coming from within the bottle to the outside, and which, when attempt is made to pour liquid into the bottle from the outside, will be automatically seated to prevent the introduction of such liquid. In 50 its further aspects the invention includes means on the valve for keeping it spaced a suitable distance at all times from the top of the cap so that the liquid will flow out when a discharge is desired.

In the preferred embodiment of the invention shown in the drawings, the idea is at-

tachable to the neck 1 of the bottle which is provided with a body 2 at its upper end. A cap 3, preferably of metal, is disposed over the neck of the bottle and is provided 60 with an inwardly turned flange 4 which will be crimped under the body 2. The cap is provided with a discharge orifice 5 threaded to receive a threaded body portion 6 having a dependent stem 7 and a head 8. 65

The stem 7 is adapted, when the body portion is screwed into the discharge orifice, to bear against the upper surface of a valve 9. This valve comprises a plate portion 10, against the upper face of which the stem 7 70 bears, and a conical body portion dependent from said plate portion. The plate portion 10 extends beyond the conical body portion and acts as a flange to rest on a washer 11, preferably of some flexible material, such 75 as rubber, to form a tight seat for the valve. The upper surface of the plate 10, at any desired point, is provided with a projection or seat 12 which prevents that portion of the plate from coming intimately in contact 80 with the inner face of the cap, so that there is always a slight space between the upper surface of the plate 10 and the cap to permit of the discharge of liquid through said space. 85

In the position of the parts shown in Fig. 1, the valve is held tightly against its seat by means of the stem 7, because the body portion 6 is screwed firmly into the discharge orifice of the cap 3. By loosening or removing this body portion 6, however, and inverting the bottle, the valve 9 will fall off its seat by gravity and the liquid from the bottle will flow out around the valve and out of the discharge opening 5, because of 95 the fact that the valve is spaced slightly from the inner surface of the cap by reason of the projection 12. However, when the bottle assumes its normal position any attempt to pour liquid into the bottle will 100 cause said liquid to bear on the upper surface of the valve and press it more firmly on its seat, namely, the washer 11.

It will thus be seen that I have provided a simple and efficient means whereby a minimum number of strong and durable parts can be applied to the neck of a bottle for the purpose of making it non-refillable. 105

What I claim is:—

A non-refillable bottle which comprises a 110 neck, a cap to be disposed over said neck, the neck having a bead at its upper end, the

cap having a flange on its lower end turned under said bead to permanently hold the cap on to the neck, said cap having a threaded aperture therein, a washer disposed 5 on the top of the neck and held thereagainst by the cap, a valve having a lower conical shaped body, and an outwardly extending circular flange adapted to rest on said washer, a projection on the upper surface of the 10 valve to prevent said surface from lying

too closely against the cap when the bottle is inverted, a plug adapted to be threaded into the threaded opening in the cap and a stem on the lower end of the plug adapted to be placed against the valve as the plug is 15 advanced to hold the valve on its seat, the withdrawal of the plug permitting the valve to move off its seat.

GEORGE A. PAGONIS.
